UNITED STATES PATENT OFFICE

CLAUDE L. POST, OF CHICAGO, ILLINOIS

SHEET FEEDING MECHANISM

Application filed March 5, 1928. Serial No. 92,631.

My invention relates to sheet feeding mechanism and has among its other objects the production of mechanism of the kind described which is convenient, durable, efficient and satisfactory for use wherever found applicable.

A particular object of the invention is to provide improved mechanism for feeding sheets of paper, envelopes, or the equivalent, to printing devices, embossing machines, folding machines, etc.

Another particular object of the invention is to provide improved mechanism adapted to feed sheets of various thicknesses without adjustment therefor.

Still another particular object of the invention is to provide improved sheet feeding mechanism adapted to feed relatively thin stock without injury thereto.

I have illustrated several forms of the invention in the accompanying drawings, each of which forms comprises means adapted to travel over a stock or row of envelopes, sheets of paper, or the equivalent, and to frictionally engage or grip the last envelope or sheet of paper in the stack or row, the envelope or sheet of paper thus engaged being withdrawn from the stack or row and advanced to printing mechanism which does not form a part of this invention.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a side elevation of sheet feeding mechanism embodying the invention;

Fig. 2 is a plan view of the improved mechanism;

Fig. 3 is a section taken on line 3--3 of Fig. 2;

Fig. 4 is a section taken on line 4--4 of Fig. 1;

Fig. 5 is a rear elevation of the improved mechanism;

Fig. 6 is an enlarged fragmentary section taken on substantially the same line as Fig. 3;

Fig. 7 is a perspective view illustrating certain details of construction of the improved mechanism;

Fig. 8 is a section taken on line 8--8 of Fig. 6;

Fig. 9 is a fragmentary section taken substantially on the same line as Fig. 3 and illustrating the manner in which the stock being fed is frictionally engaged by the friction member forming a part of the improved mechanism;

Fig. 10 is a side elevation of sheet feeding mechanism embodying another form of the invention;

Fig. 11 is a plan view of the mechanism shown in Fig. 10;

Fig. 12 is a section taken on line 12--12 of Fig. 11;

Fig. 13 is a section taken on line 13--13 of Fig. 11;

Fig. 14 is an end elevation of the mechanism shown in Fig. 13;

Fig. 15 is a section taken on line 15--15 of Fig. 11;

Fig. 16 is an enlarged section through one of the feeding members adapted to frictionally engage the stock being fed;

Fig. 17 is a section taken on line 17--17 of Fig. 16; and

Fig. 18 is a fragmentary section through a sheet feeding device embodying still another form of the invention.

Referring for the present to Figs. 1 to 9, inclusive, wherein I have shown one form of the invention embodied in mechanism adapted to feed sheets of paper, envelopes, or the equivalent, to printing mechanism of the type shown in my co-pending application, Serial No. 700,403, filed Mar. 19, 1924, the reference character 20 designates generally a frame for the improved feeding mechanism and the reference character 21 designates generally the frame of the printing machine. However, it is to be understood that the present invention is not limited to printing machines of the character indicated nor is it limited to

printing machines in general as the improved feeding mechanism is adapted to feed envelopes, sheets of paper, or the equivalent, to embossing machines, folding machines, wrap-
5 ping machines or any other machine adapted to use sheets or envelopes.

As best shown in Figs. 1 and 2, the printing mechanism comprises a shaft 23 rotatably journaled in the frame 21 and provided
10 with a sprocket 24 meshing with a sprocket chain 25 which operatively connects the sprocket with any suitable source of power, this construction being substantially identical
15 with the construction shown in the afore-mentioned co-pending application. Pinned to the shaft 23 are feed rolls 27 which co-
operate with a feed roll 28 to advance envelopes or sheets of paper to printing rolls (not shown), the roll 28 having trunnions 29
20 rotatably journaled in the frame 21. The means for driving the roll 28 comprises a gear 30 fixed to one of the trunnions 29 and ar-
ranged to mesh with a pinion 31 mounted upon the shaft 23.

25 The improved feeding mechanism may be driven by means comprising a sprocket 24 secured to the shaft 23 adapted to mesh with a sprocket chain 35 which meshes with a sprocket 36 fixed to a shaft 37 rotatably jour-
naled in the frame 20. Pinned to the shaft 37 is a pulley 39 which is aligned with a pulley 40 pinned to a shaft 41 rotatably jour-
naled in the frame 20, a belt 42 being trained over the pulleys 39 and 40 in such manner
35 that the shafts 37 and 41 rotate in opposite directions.

Constrained to rotate with the shaft 37 and mounted thereon are rotary feed members or rollers 43 which cooperate with rotary
40 feed members or rollers 44 rotatably jour-
naled upon stud shafts 45 mounted in the frame 20 (see Fig. 4). In practice I have had good results by employing rollers 44 having treads formed of rubber. It will be noted
45 that the rotary feed members 43 and 44 are adapted to advance the stock to the feed rolls 27 and 28. Pinned to the shaft 41 are sprock-
ets 47 meshing with sprocket chains 48 which also mesh with sprockets 49 rotatably jour-
naled upon a shaft 50, which is, in turn, rotatably journaled in the frame 20. Interposed
50 between the sprocket chains 48 and arranged to travel therewith are pins 53 which carry feeding devices each feeding device being
55 indicated in general by the reference character 54. As best illustrated in Fig. 2, each feeding device 54 comprises bent bars 55 having hubs 56 rotatably journaled upon one of the pins 53, the hubs 56 being spaced to ac-
60 commodate a collar 58 which prevents dis-
placement of the hubs longitudinally of the pin. Interposed between each pair of bent bars 55 are discs 59 rotatably journaled upon a pin 60 mounted in the bars and secured to
65 the bars at their free ends is a holder 63 from

which a friction member 64 projects, the friction member 64 being formed from any suitable material which has a relatively high coefficient of friction. I preferably form the friction members 64 from sponge rubber, or
70 the equivalent. It will be noted that the friction members 64 are retained in the holders 63 by frictional engagement therewith, a pin 66 being provided in each holder to limit inward displacement of the friction member.
75

The angular displacement of the feeding devices 54 around their respective pins 53 is limited by loops 68 formed of suitable flexible material, such as twine (see Fig. 6). When the mechanism is in operation, the loops 68 insure that the feeding devices 54 will properly approach a feed table 69 disposed beneath the sprocket chains 48 and provided with longitudinal slots 70 aligned with the discs 59. Mounted in the feed table 69 are friction elements 72 formed from sponge rubber, or any other suitable material, each friction element being secured in a channel 73 which is adjustably secured to the table by bolts 75 having nuts 76 threaded thereon
80 adapted to retain the channel in a plurality of adjusted positions against the action of compression springs 77 wound around the bolts 75. Guide members 78 are mounted upon the table 69 by means comprising bolts 79 secured to the table and arranged to project through slots 80 formed in the guide members, wing nuts 81 being provided for locking the guide members in their adjusted positions.
85

A magazine 85 is provided at the rear end of the table 69 and preferably comprises a vertically disposed plate 86 which is rigidly secured in the frame 20 and is thereby held against movement relative to the table 69.
90 Arranged adjacent the plate 86 is a substantially horizontal plate 89 adapted to carry the stock which is to be fed to the printing mechanism, the plate 89 being adapted to be vertically displaced between two guides 90 secured to the plate 86 by bolts 91 or the equivalent screw-threaded into the plate 86 passed through slots 92 formed in the guides. As best shown in Fig. 2, the guides 90 are preferably aligned with the guide members 78. Positioned upon the rear end of the plate 89 are guides 94 which prevent lateral displacement of the stock relative to the plate 89 and are adjustably secured to the plate by means comprising bolts 95 fixed to the plate and arranged to project through slots 96 formed in the guides, wing nuts 97 being provided for securing the guides in their adjusted positions. Each end of the plate 89 is riveted to an L-shaped member 99 and the L-shaped members are provided with pins 100 adapted to ride in depressions 101 formed in the frame 20. Projecting from the end of each pin 100 is a pin 103 of smaller diameter to which one end of a spring 104 is secured, the other end
105
110
115
120
125
130

of the spring being secured to a pin 105 projecting from the frame 20. The pins 103 project through slots 103a formed in the frame 20. The springs 104 tend to elevate the plate 89 but are controlled by means comprising a roller 106 journaled upon a pin 107 and engaged by cams 109 secured to a shaft 110 rotatably journaled in the frame 20.

Interposed and secured to the shaft 110 and the pins 100 are lazy tongs 112 comprising a plurality of bars 113 having their ends pivoted to each other as at 114 and being pivoted to each other intermediate their ends by pins 115. Enlarged portions of the pins 115 ride in the recesses 101 as shown in Figs. 1 and 5. It will be noted that in two instances the pins 115 are omitted and are replaced by the pin 107 which extends from one lazy tong to the other.

It is readily understood that if the cams 109 are angularly displaced to permit the roller 106 and the pin 107 to approach the shaft 110, the springs 104 will contract and raise the plate 89 a distance exceeding the distance through which the pin 107 travels. At certain times during the operation of the mechanism, the cams 109 are angularly displaced by means comprising a sprocket 118 secured to the shaft 110 and meshed with a sprocket chain 119, which also meshes with a sprocket 120 rigidly secured to the shaft 50. Also rigidly secured to the shaft 50 is a ratchet 122 which is engageable by a pawl 123 pivoted by a pin 124 upon one end of a lever 125, the lever 125 being pivoted intermediate its ends to the frame 20 by a pin 126. The pawl 123 is urged toward the ratchet 122 by a leaf spring 128 mounted upon the lever 125 but is normally held out of engagement therewith by a bent rod 130 projecting from a collar 131 rigidly secured to one end of a shaft 133 pivoted in the frame 20, the shaft 133 being provided with a crank portion 134 intermediate its ends, which crank portion is engageable by the discs 59 when they pass through the slots 70 in the table 69. A spring 136 having one end fastened to the bent rod 130 and having its other end fixed to a pin 137 projecting from the frame 20 yieldingly holds the bent rod in the position wherein it holds the pawl 123 out of engagement with the ratchet 122. A pitman 139 has one end projecting through an aperture 140 formed in the lever 125, springs 141 and 142 being interposed between the lever and a shoulder 143 formed upon the pitman and a nut 144 screw-threaded thereon. The other end of the pitman 139 is pivoted by a screw 146 to a disc 147 fixed to the shaft 41, the longitudinal axis of the screw 146 being spaced from the axis of rotation of the disc. Obviously, when the shaft 41 is rotated, the pitman 139 oscillates the lever 125 so that if the pawl 123 engages the ratchet 122, the ratchet will be advanced in a step by step motion and it, in turn, will

rotate the shaft 50. This rotation is transmitted to the shaft 110 by the sprockets 118 and 120 and the sprocket chain 119.

The operation of the above described mechanism is substantially as follows: A supply of envelopes, sheets of paper, or the equivalent, is placed in the magazine 85, a portion of the envelopes or sheets being pushed forward upon the table 69, as illustrated in Fig. 9. The mechanism is then set in motion, whereupon the feeding devices 54 are continuously advanced by the sprocket chains 48 in the direction indicated by the arrows in Fig. 3. When one of the feeding devices 54 comes in contact with the stock its discs 59 ride thereon until they pass over the piece of stock nearest the rotary feed members 43 and 44 and drop into the slots 70. This permits the friction member 64 to engage said piece of stock and to advance it until it is engaged by the rotary feed members 43 and 44. The rotary feed members 44 hold the piece of stock into engagement with the members 43, which are mounted upon the shaft 37. The members 43 and 44 advance the stock to the feed rolls 27 and 28, which, in turn, advance the stock to the printing mechanism (not shown). The manner in which the friction members 64 engage the stock when the discs 59 pass therefrom is best illustrated in Fig. 9. The feeding devices 54 are preferably so designed that their weight is sufficient to cause the friction members 64 to effectively engage the stock, but a spring may be used if desired to urge the friction members against the stock. The friction elements 72 insure that only one piece of stock will be withdrawn by each friction member 64, each time the friction member is advanced over the table 69. When an insufficient supply of stock is disposed upon the table 69 to prevent the discs 59 from engaging the crank portion 134 when they fall into the slots 70, the shaft 133 will be angularly displaced by the discs 59 to bring the bent rod 130 into a position wherein it permits the pawl 123 to engage the ratchet 122. Then as the pitman 139 is continuously reciprocated and it, in turn, oscillates the lever 125, the pawl 123 will advance the ratchet so that the cams 109 will be angularly displaced in the manner described above. The springs 104 will then raise the plate 89 to bring more stock into the path of the feeding devices 54, which then distribute the stock upon the table until the discs 59 are again prevented from engaging the crank portion 134.

Referring now to Figs. 10 to 17, inclusive, wherein I have shown another form of the invention embodied in mechanism adapted to feed envelopes, sheets of paper, or the like, to a printing machine which comprises the above described frame 21, the feed rolls 27 and 28, the shaft 23, the sprocket 24 and the sprocket chain 25, the reference character 20a

designates generally a frame adapted to hold the improved mechanism. Journaled in the frame 20a is a shaft 37a which is driven from the shaft 23 by means comprising sprockets 34a and 36a, and a sprocket chain 35a (see Fig. 10). Secured to the shaft 37a is a gear 155, which meshes with a gear 156 secured to a shaft 41a journaled in the frame 20a. Also secured to the shaft 37a are rotary feed members 43a which cooperate with rotary feed members 44a rotatably journaled upon stud shafts 45a mounted in the frame 20a. A plurality of sprockets 47a fixed to the shaft 41a mesh with sprocket chains 48a which also mesh with sprockets 49a rotatably journaled upon a shaft 50a, the shaft 50a being journaled in the frame 20a. Interposed between the sprocket chains 48a and carried thereby are pins 53a upon which feeding devices 54a are mounted, each feeding device 54a preferably comprising bent bars 55a having hubs 56a journaled upon the associated pin 53a. Interposed between each pair of hubs 56a is a collar 58a secured to the pin 53a and adapted to prevent displacement of the feeding devices longitudinally of the pin. A pin 60a carried by each pair of bent bars 55a rotatably journals discs 59a and upon the free ends of the bent bars 55a a holder 63a is mounted for holding a friction member 64a preferably formed of sponge rubber, or the equivalent. As best illustrated in Figs. 16 and 17, the friction member 64a is slidably mounted in the holder 63a and is secured to a backing member 160 which is secured to a screw 161 by a pin 162 adapted to ride in a slot 163 formed in the screw. The screw 161 is threaded in the holder 63a and may be manipulated to raise or lower the friction member 64a in the holder. Angular displacement of the feeding devices 54a relative to the pins 53a is limited by loops 68a which connect the pins 60a with pins 69b carried by the chains 48a. The chains 48a are adapted to advance the feeding devices 54a over an inclined table 69a which serves as a magazine, the direction of travel of the chains 48a being indicated by arrows in Fig. 12. The table 69a is provided with slots 70a through which the discs 59a may pass to engage a crank portion 134a formed upon a shaft 133a pivoted in the frame 20a. Friction elements 72a formed of rubber, or the equivalent, are adjustably mounted in the table 69a and form the same function as the aforementioned friction elements 72. One end of the shaft 133a has a lever 130a secured thereto, the lever being adapted to hold a pawl 123a out of engagement with a ratchet 122a secured to a shaft 166 journaled in the frame 20a. Secured to the shaft 166 is a shaft 170 having a sprocket 171 secured thereon. The pawl 123a is pivoted intermediate its ends to a pitman 139a which has one of its ends pivoted to a disc 147a by a screw 146a, the

disc 147a being fixed to the shaft 41a. The other end of the pitman 139a rides upon a hub 172 formed integral with the gear 168. If the lever 130a is displaced to permit the pawl 123a to engage the ratchet 122a and the pitman 139a is reciprocated the pawl 123a will advance the ratchet 122a in a step by step motion and this motion will be transmitted to the shaft 170 by the gears 168 and 169. Meshing with the sprocket 171 mounted upon the shaft 170 is a sprocket chain 175 which also meshes with a sprocket 176 journaled upon a shaft 177 mounted at the rear end of the table 69a. It will be noted that one leg of the sprocket chain 175 rides upon the table 69a.

Mounted upon the table 69a are L-shaped guide members 178 riveted to bracket members 179 which are adjustably secured to the table 69a by means comprising bolts 180 secured to the table, the bolts being adapted to pass through slots 181 formed in bracket members and wing nuts 182 being provided for securing the bracket members in their adjusted positions.

The operation of the improved mechanism illustrated in Figs. 10 to 17, inclusive, is substantially as follows:

The stock which is to be fed to the printing mechanism is arranged upon the table 69a in substantially the same manner as the stock arranged in Fig. 9. However, a relatively large amount of stock can be disposed upon the table 69a, the greater portion of it being positioned upon that leg of the chain 175 which travels over the table. When the mechanism is set in motion, the chains 48a advance the feeding devices 54a in the manner indicated by the arrows in Fig. 12. When a feeding device 54a comes in contact with the stock, the discs 59a ride upon the stock until they pass over it and drop into slots 70a, whereupon the associated friction member 64a engages that piece of stock which is positioned nearest to the rotary feed members 43a and 44a and advances said piece of stock to the rotary feed members. The rotary feed members then advance the stock to the feed rolls 27 and 28 which, in turn, deliver it to the printing mechanism (not shown). When sufficient stock has been removed from the table 69a to permit the discs 59a to engage the crank portion 134a, the crank portion 134a is displaced and the shaft 133a is rotated sufficiently to bring the lever 130a out of the position wherein it holds the pawl 123a disengaged from the ratchet 122a. The reciprocating pitman 139a then causes the pawl 123a to advance the ratchet 122a in a step by step motion and this motion is imparted to the sprocket chain 175 in the manner above described. The sprocket chain then advances the stock until it prevents the disc 59a from engaging the crank portion 134a, whereupon the lever 130a is restored

85

90

95

100

105

110

115

120

125

130

to the position wherein it holds the pawl 123a out of engagement with the ratchet 122a.

As described above, the friction elements 72 and 72a are adjustably mounted with respect to the tables 69 and 69a, respectively. This permits the friction elements to be adjusted for various kinds of stock the apparatus is employed to handle. Whenever paper having a glazed surface is being handled, the friction elements 72 and 72a are adjusted so that they project a relatively large distance above the tables 69 and 69a, respectively, so that the stock is effectively engaged thereby and the feed devices 54 and 54a are prevented from advancing more than a single sheet thereof at the time. When a rougher stock is used, the friction elements are preferably adjusted so that their upper surfaces project slightly above or lie substantially flush with the upper surface of the tables.

In Fig. 18, I have shown preferred construction which may be employed in place of some of the construction shown in Figs. 1 to 17, inclusive, the preferred construction being employed in means for receiving the stock when it is fed from the tables 69 or 69a by the friction members 64 or 64a, respectively. Thus, the reference character 69c indicates a feed table which may represent either the feed table 69 or the feed table 69a, the feed table 69c being mounted in a frame 20c which is fixed with respect to one end of a frame 21c provided for the printing mechanism (not shown). Friction members 64c carried by chains 48c in the same manner as the friction members 64 or 64a are carried by the chains 48 or 48a respectively, and are adapted to advance the stock from the table 69c to rotary feed members or rolls 43c and 44c, which are, in turn, adapted to deliver the stock to sheet advancing mechanism mounted in the frame 21c and comprising sprocket chains 190. The sprocket chains 190 have lugs 191 adapted to engage the stock and advance it to the printing mechanism (not shown), this sheet advancing mechanism being substantially of the same construction as shown in the above mentioned copending application. It will be noted that the stock is advanced between guide members 193 and 194 and that it is caused to engage a toothed wheel 195 by a roller 196. The toothed wheel 195 is fixed to a shaft 197 upon which sprockets are mounted for the sprocket chains 190, the shaft 197 being driven by means as shown in the aforementioned application. The sprocket chains 48c mesh with sprockets 47c fixed to a shaft 41c which is driven by means comprising a sprocket chain 25c operatively connecting a sprocket fixed to the shaft 41c with the means for driving the printing mechanism (not shown). Pinned or otherwise secured to the shaft 41c is a pulley 40c aligned with a pulley 39c fixed to a shaft 37c which carries the

rolls 43c. A belt 42c is trained over the pulleys 40c and 39c in such manner that the shafts 37c and 41c rotate in opposite directions. The rolls 44c are mounted upon stud shafts 45c fixed in the frame 20c.

It will be noted that in the construction shown in Fig. 18, the feed rolls 27 and 28 are not employed and that the feed rolls 43c and 44c feed stock directly to the sheet advancing mechanism of the printing machine.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In feeding mechanism, a table for holding a plurality of articles, non-reciprocating means disposed above the articles and movable relative thereto for engaging the articles one at the time and advancing them, and means controlled by the first-mentioned means for replenishing the supply of articles upon the table.

2. In feeding mechanism, a table for holding a plurality of articles, non-reciprocating means disposed above the articles and movable relative thereto for frictionally engaging the articles one at the time and advancing them, and means controlled by the first-mentioned means for replenishing the supply of articles upon the table.

3. In feeding mechanism, means for holding a plurality of articles arranged in overlapping alignment, non-reciprocating means movable relative to the first-mentioned means for engaging an article at one end of the row and advancing it, and means controlled by said movable means for advancing the row of articles substantially as a unit.

4. In feeding mechanism, means for holding a plurality of articles arranged in overlapping alignment, non-reciprocating means movable relative to the first-mentioned means for frictionally engaging an article at one end of the row and advancing it, and means controlled by said movable means for advancing the row of articles substantially as a unit.

5. In feeding mechanism, a table for holding a plurality of articles, non-reciprocating means disposed above the articles and movable relative thereto for engaging the articles one at the time and advancing them, and means disposed below the articles and controlled by the first-mentioned means for advancing a plurality of the articles simultaneously.

6. In feeding mechanism, a table for holding a plurality of articles, non-reciprocating means for frictionally engaging and advanc-

ing them one at the time, a magazine for holding a supply of said articles, and means controlled by said first-mentioned means for ejecting articles from the magazine to replenish the supply upon the table.

- 5 7. In feeding mechanism, a table for holding a plurality of articles, non-reciprocating means movable over the articles for frictionally engaging and advancing them one at the time, a magazine for holding a supply of said articles, and means controlled by said movable means for ejecting articles from the magazine to replenish the supply upon the table.
- 10 8. In feeding mechanism, means for holding a row of articles, non-reciprocal means arranged to ride over the upper surface of said articles and to advance the last article in said row, and means controlled by said movable means for advancing a plurality of said articles in unison.

- 15 9. In feeding apparatus, the combination with a feeding device comprising a rotatable disc and a friction member, of means for advancing the feeding device over a plurality of articles arranged in overlapping alignment, the feeding device being rotatable into engagement with said articles and the friction member being arranged to engage the last article when the disc passes therefrom.

- 20 10. In feeding apparatus, the combination with a friction member, of rotatable means associated with the friction member for advancing it over a row of articles, said friction member being rotatable into engagement with the last article in the row and to separate it from the other articles.

- 25 11. In feeding apparatus, the combination with a friction member, of means traveling continuously in a fixed path for advancing the friction member over a row of articles, means adapted to ride upon the articles for holding the friction member out of contact therewith, said friction member arranged to engage and advance one of said articles when said means adapted to ride upon the articles passes out of engagement therewith.

- 30 12. Sheet feeding mechanism comprising a table for holding the sheets, a friction member, non-reciprocating means for advancing the friction member over the table, and normally stationary means adapted to engage the bottom surfaces of said sheets for preventing the friction member from moving more than one of said sheets.

- 35 13. Sheet feeding mechanism comprising a table for holding a row of the sheets, a gripping member, non-reciprocating means for advancing the gripping member over the table, and normally stationary means for preventing the gripping member from moving more than one of said sheets.

- 40 14. Sheet feeding mechanism comprising a table for holding the sheets, a friction member, means for advancing the friction

member over the table, adjustable means adapted to engage the bottom surfaces of said sheets for preventing the friction member from moving more than one of said sheets, and rotatable means arranged to receive the sheets from the friction member.

45 15. Sheet feeding mechanism comprising a table for holding the sheets, non-reciprocating means for advancing the sheets one at the time, and normally stationary means for frictionally engaging the bottom surfaces of the sheets to prevent more than one sheet from being advanced at one time.

50 16. Sheet feeding mechanism comprising a table for holding the sheets, means for frictionally engaging and advancing the sheets one at the time, and means adjustably mounted on the table for frictionally engaging the sheets to prevent more than one sheet from being advanced at one time.

55 17. Sheet feeding mechanism comprising a table for holding the sheets, means for advancing the sheets one at the time, and adjustable means on the table for frictionally engaging the sheets to prevent more than one sheet from being advanced at one time.

60 18. Sheet feeding mechanism comprising a table for holding the sheets, means for frictionally engaging and advancing the sheets one at the time, and adjustable means on the table for frictionally engaging the sheets to prevent more than one sheet from being advanced at one time.

65 19. Sheet feeding mechanism comprising a table for holding the sheets, an endless chain arranged to travel over the table, a holder carried by the chain, and a friction member adjustably carried by the holder and engageable with the sheets.

70 20. In a sheet feeding mechanism, the combination with a feed table adapted to hold a feathered bank of sheets, of means traveling continuously in a fixed path and disposed above said table and movable relative thereto and engageable with said bank of sheets for further feathering or combing out said sheets and thereafter advancing the top sheet only of said bank.

75 21. In a sheet feeding mechanism, the combination with a feed table whereon a feathered bank of sheets may be supported, frictional retarding means mounted on the table and adjustable relative to the surface thereof, and means disposed above the table and movable with respect thereto for advancing one sheet at the time from said bank of sheets.

80 22. In a sheet feeding mechanism, the combination with a table adapted to receive a feathered bank of sheets, of means traveling continuously in a fixed path for advancing one sheet at the time from said bank of sheets, a supply stack of sheets adjacent the table, said sheet advancing means being

adapted to replenish the bank of sheets from said supply stack.

23. In a sheet feeding mechanism, the combination with a table adapted to receive a feathered bank of sheets, of means traveling continuously in a fixed path for advancing one sheet at the time from said bank of sheets, a supply stack of sheets adjacent the table, said sheet advancing means being adapted to replenish the bank of sheets from said supply stack and means governed by the supply of sheets in said bank for advancing said supply stack.

24. In a sheet feeding mechanism, the combination with a feed table adapted to receive a feathered bank of sheets, of a supply table adapted to support a continuation of said feathered bank of sheets, conveying means associated with said supply table for replenishing the bank of sheets on said feed table from said supply table and means traveling continuously in a fixed path movable over said feed table for advancing the sheets thereon one at the time.

25. In a sheet feeding mechanism, the combination with an inclined feed table, of an inclined supply table formed substantially as an extension of said feed table, the said feed and supply tables being adapted to receive a continuous feathered bank of sheets, means traveling continuously in a fixed path above said feed table for advancing sheets therefrom one at the time and means associated with said supply table for advancing the bank of sheets as a unit.

26. In a sheet feeding mechanism, the combination with an inclined feed table, of an inclined supply table formed substantially as an extension of said feed table, the said feed and supply tables being adapted to receive a continuous feathered bank of sheets, means above said feed table for advancing sheets therefrom one at the time and means associated with said supply table for advancing the bank of sheets as a unit and means governed by the supply on said feed table for rendering said last mentioned means effective or ineffective.

27. In a feeding mechanism, a table for holding a plurality of articles, means movable relative to said table and articles for engaging and moving the latter one at the time and means adjustably embodied in the surface of said table for frictionally engaging and retarding the movement of said articles.

28. Sheet feeding mechanism comprising a table for holding the sheets, a reservoir for holding a supply of sheets for said table, a feeding mechanism for advancing the sheets one at a time on said table, means for intermittently causing the supply of sheets from said reservoir, and means operatively connected to said feeding mechanism for actuating said intermittent means, said feeding

mechanism continuing to function while said actuating means is in operation.

29. Sheet feeding mechanism comprising an inclined feed table, an inclined supply table formed substantially as an extension of said feed table, a feeding mechanism for advancing the sheets one at a time on said feed table, means for intermittently supplying sheets from said supply table, and means operatively connected to said feeding mechanism for actuating said intermittent means, said feeding mechanism continuing to function while said actuating means is in operation.

30. Sheet feeding mechanism comprising a table for holding the sheets, a reservoir for holding a supply of sheets for said table, a non-reciprocating feeding mechanism for advancing the sheets one at a time on said table, means for intermittently causing the supply of sheets from said reservoir, and means associated with said feed mechanism for actuating said intermittent means, said feeding mechanism continuing to function while said actuating means is in operation.

31. Sheet feeding mechanism comprising an inclined feed table, an inclined supply table formed substantially as an extension of said feed table, a non-reciprocating feeding mechanism for advancing the sheets one at a time on said feed table, means for intermittently supplying sheets from said supply table to said feed table, and means associated with said feeding mechanism for actuating said intermittent means, said feeding mechanism continuing to function while said actuating means is in operation.

32. Sheet feeding mechanism comprising an apertured table for holding the sheets, a non-reciprocating reservoir for holding a supply of sheets for said table, a feeding mechanism for advancing the sheets one at a time on said table, means for intermittently causing the supply of sheets from said reservoir, and a member associated with said feeding mechanism and compressible within the apertures of said table for cooperating with said intermittent means and rendering the same effective.

33. Sheet feeding mechanism comprising an apertured table for holding the sheets, a reservoir for holding a supply of sheets for said table, a feeding mechanism for advancing the sheets one at a time on said table, means for intermittently causing the supply of sheets from said reservoir, and a member associated with said feeding mechanism and compressible within the apertures of said table for cooperating with said intermittent means and rendering the same effective, said feeding mechanism continuing to function while said intermittent means is in operation.

34. In feeding mechanism, means for holding a plurality of articles in overlapping alignment, and means travelling continuously

in a fixed path and movable over said articles and in a plane substantially parallel to that of their exposed surfaces and adapted to engage only the last one of said articles for advancing it.

35. In feeding mechanism, means for holding a plurality of articles in overlapping alignment, and means travelling continuously in a fixed path and movable over said articles and in a plane substantially parallel to that of their exposed surfaces and adapted frictionally to engage only the last one of said articles for advancing it.

36. In feeding mechanism, means for holding a plurality of articles in overlapping alignment, means movable over a row of said articles in a plane substantially parallel to that of the adjacent surfaces thereof, a frictional member carried by said movable means, and rotatable means also carried by said movable means and adapted to ride upon adjacent surfaces of said articles for maintaining said friction member out of engagement therewith, said friction member being arranged to engage and advance one of said articles when said rotatable means passes out of engagement therewith.

37. In feeding mechanism, means for holding a plurality of articles in overlapping alignment, means movable over a row of said articles in a plane substantially parallel to the exposed surfaces thereof, rotatable means carried by said movable means and adapted to ride over said articles, and a friction member carried by said movable means adapted to engage and advance one of said articles when said rotatable means passes out of engagement therewith.

38. In feeding mechanism, means for holding a plurality of articles in overlapping alignment, non-reciprocating means movable over a row of said articles in a plane substantially parallel to the exposed surfaces thereof, means carried by said non-reciprocating means and adapted to ride over said articles, and a friction member carried by said non-reciprocating means adapted to engage and advance one of said articles when said means adapted to ride on the articles passes out of engagement therewith.

39. Sheet feeding mechanism comprising a table for holding sheets, a reservoir for holding a supply of sheets for said table, a feeding mechanism for advancing the sheets one at a time on said table, means for intermittently causing a supply of sheets from said reservoir, and means operatively connected to said feeding mechanism and governed by the supply of sheets on said table for actuating said intermittent means, said feeding mechanism continuing to function while said actuating means is in operation.

40. Sheet feeding mechanism comprising an inclined feed table, an inclined supply table formed substantially as an extension of

said feed table, a feeding mechanism for advancing sheets one at a time on said feed table, means for intermittently supplying sheets from said supply table, and means operatively connected to said feeding mechanism and governed by the supply of sheets on said feed table for actuating said intermittent means, said feeding mechanism continuing to function while said actuating means is in operation.

47. Sheet feeding mechanism comprising an apertured table for holding the sheets, a reservoir for holding a supply of sheets for said table, a feeding mechanism for advancing the sheets one at a time on said table, means for intermittently causing the supply of sheets from said reservoir and a member associated with said feeding mechanism and depressible within the apertures of said table by gravity for cooperating with said intermittent means and rendering the same effective.

48. Sheet feeding mechanism comprising an apertured table for holding the sheets, a reservoir for holding a supply of sheets for said table, a frictional feeding member for advancing the sheets one at a time on said table, means for intermittently causing the supply of sheets from said reservoir, a rotatable disk movable over said table and depressible within the apertures thereof for cooperating with said intermittent means and rendering the same effective, said disk being connected with said frictional member so as to maintain the same out of engagement with said sheets until said disk has been depressed into a flap and thereupon bringing said member into feeding engagement with a sheet.

49. Sheet feeding mechanism comprising an apertured table for holding the sheets, a reservoir for holding a supply of sheets for said table, a frictional feeding member for advancing the sheets one at a time on said table, means for intermittently causing the supply of sheets from said reservoir, a non-frictional member movable over said table, and depressible within the apertures thereof for cooperating with said intermittent means and rendering the same effective, said non-frictional member being connected with said frictional member so as to maintain the same out of engagement with said sheets until said disk has been depressed into a flap and thereupon bringing said member into feeding engagement with a sheet.

50. Sheet feeding mechanism comprising an apertured table for holding the sheets, a reservoir for holding a supply of sheets for said table, a feeding mechanism for advancing the sheets one at a time on said table, means for intermittently causing the supply of sheets from said reservoir, and a rotatable disk associated with said feeding mechanism and depressible within the apertures of said table for cooperating with said intermittent means and rendering the same effective, said feeding mechanism continuing to function while said intermittent means is in operation.

51. In a feeding mechanism the combination of a table, means for successively feeding articles from said table, means for moving the table to present an article to the feeding means, and means for controlling said movement of said table, said means including an eccentric, a lazy tong mechanism located

between the table and eccentric, and means for moving the eccentric a prescribed distance upon removal of an article from said table.

52. In a feeding mechanism the combination of a table, means for successively feeding articles from said table, means for moving the table to present an article to the feeding means, and means for controlling said movement of said table, said means including an eccentric, a lazy tong mechanism, located between the table and eccentric, a spring normally urging the table toward the eccentric, and means for moving the eccentric a prescribed distance upon removal of an article from said table.

53. In a feeding device, a table for carrying a plurality of articles, means movable from one end to the opposite end of said table having means for engaging an article and conveying said article along the table, and means for presenting the article engaging means to said table for engagement with said article.

54. In a feeding device, a table for carrying a plurality of articles, means movable from one end to the opposite end of the table having means pivotally connected thereto for engaging an article and conveying said article along the table, and means for preventing the article engaging means to said table for engagement with said article.

55. In a feeding device, a table for carrying a plurality of articles, an endless element operable along said table, article advancing means carried by said element, means for presenting an article to said advancing means, and means carried by said endless element providing an element of means for actuating said last mentioned means.

56. In a feeding device, a table for carrying a plurality of articles, means for conveying an article along the table and means for advancing an article to the conveying means, said conveying means including a truck having means for engaging an article and having means providing an element of means for actuating said article advancing means.

57. In a feeding device, a table for carrying a plurality of articles, said table being provided with a slot which extends inwardly of the table from one end of the table, article advancing means, an end of which is located adjacent the inner termination of said slot, article conveying means located above the slot and extending from said termination of the advancing means to adjacent the opposite termination of the slot.

58. In a feeding device, a table for carrying a plurality of articles, said table being provided with a slot which extends inwardly of the table from one end of the table, article advancing means, an end of which is located adjacent the inner termination of said slot, article conveying means located above the

slot and extending from said termination of the advancing means to adjacent the opposite termination of the slot, and means located adjacent said slot providing an element of means for controlling operation of the article advancing means.

59. In a feeding device, a table for carrying a plurality of articles, said table being provided with a slot which extends inwardly 10 of the table from one end of the table, article advancing means, an end of which is located adjacent the inner termination of said slot, article conveying means located above the slot and extending from said termination of 15 the advancing means to adjacent the opposite termination of the slot, said conveying means having an element which enters the slot for engagement with means for controlling operation of the article advancing means.
20. In testimony whereof, I have hereunto signed my name.

CLAUDE L. POST.
